UNITED STATES PATENT OFFICE.

ANDREW C. SAXE, OF WINSTED, CONNECTICUT.

ELECTRIC SOCKET.

Application filed April 18, 1924. Serial No. 707,353.

My invention relates more especially to the class of devices that are employed for temporarily connecting a device with a source of electricity, and an object of my invention, among others, is to provide a device of this class that shall be simple in construction and particularly efficient in use.

One form of device embodying my invention and in the construction and use of which 10 the objects herein set out, as well as others, may be attained is illustrated in the accompanying drawings, in which—

Figure 1 is a side view of my improved socket.

15 Figure 2 is a similar view of one of the members of said socket.

Figure 3 is a view in lengthwise central section through said socket showing the position of the parts when the socket is disconnected.

20 Figure 4 is a view similar to Figure 3, the section however being broken out and illustrating the position of the parts when the socket is connected to a device.

25 Figure 5 shows a perspective view of several of the parts of the socket relatively disconnected.

In the accompanying drawings I have shown a case comprising a socket that is 30 preferably formed in halves 6 that are united as by means of screws 7 in a manner common to devices of this class, this case having an opening through which a cable 8 extends, the wires constituting the cable being attached at their inner ends to binding posts or screws 9 in any well known manner.

35 My improved device comprises a socket composed of two jaws, a supporting jaw 10 and a pivoted jaw 11. The supporting jaw 10 is secured within a recess 12 in the socket and the pivoted jaw is mounted upon the supporting jaw.

It will be understood that in most installations there will be two contacts each comprising a supporting and a pivoted jaw and each located in a recess 12 in the case 6, one-half of each of said recesses being formed in each of the case members 6 that comprise the case as a whole.

40 In attaching the pivoted jaw 11 to the supporting jaw two posts 13 are provided upturned from opposite sides of the jaw 10 and pivots 14 project from opposite sides of the jaw 11, being formed preferably integral therewith. The jaw 10 has a rearward extension 15 with posts 16 upturned from op-

posite sides thereof and preferably integral therewith, and the jaw 11 has a bent rear end constituting a strut rest 17.

A strut 18 has a cross bar 19, the ends of which are formed as pivots that enter openings in the posts 16, and a spring 20 is mounted on the strut 18 with one end thrusting against the rest 17 and its opposite end thrusting against the cross bar 19. The end 45 of the strut projects into an opening 21 in the rest 17. The opening 21 is so positioned with respect to the pivots at the ends of the bar 19 that the end of the strut will be on that side of a line passing through the pivots at 50 the end of the bar 19 and the pivots 14 as to normally, under the thrust of the spring 20, close the jaws together, that is, force the jaw 11 toward the jaw 10, and this force exerted to close the jaws together will be greater when a pin 22, forming a part of the electrical connection, is forced inwardly between the jaws so that a firm and efficient contact is made between the terminal comprising the 55 two jaws and the terminal comprising the pin 22.

The description hereinabove refers to one of the terminals only, but it will be understood that the two terminals common to a plug are both of the same construction and 60 that the above description, therefore, applies equally to both of such terminals.

In accordance with the provisions of the patent statutes I have described the principles of operation of my invention, together 65 with the device which I now consider to represent the best embodiment thereof; but I desire to have it understood that the device shown is only illustrative and that the invention may be carried out by other means 70 and applied to uses other than those above set out.

I claim—

1. An electric socket having a recess, and 75 a terminal located in said recess, said terminal comprising a supporting jaw with posts integrally formed therewith and upturned from opposite sides thereof, a jaw having pivots integral therewith and projecting from its opposite edges and located 80 in openings in said posts, an extension from the end of said supporting jaw, means for attachment of a wire to said extension, and a spring thrusting against the supporting 85 and pivoted jaws to force them toward each other.

2. An electric socket having a recess, and

- a terminal located in said recess, said terminal comprising a supporting jaw, a jaw pivotally mounted on said supporting jaw, an extension from said supporting jaw, 5 posts upturned from opposite sides of said extension, a strut pivotally mounted between said posts and in engagement with said pivoted jaw, a spring mounted on said strut, and means for attachment of a wire to said 10 extension.
3. An electric socket having a recess, and a terminal located in said recess, said terminal comprising a supporting jaw, an extension from the rear end of said jaw, said 15 extension ending in a terminal offset from the plane of said extension, posts upturned from opposite sides of said extension, a jaw pivotally mounted on said supporting jaw, and a spring having its thrust resisted at 20 one end by said posts and thrusting with its opposite end against said pivoted jaw to force the jaws toward each other.
4. An electric socket having a recess, and a terminal located in said recess, said terminal comprising a supporting jaw, posts upturned from opposite sides of said jaw, an extension from the end of said jaw, posts upturned from opposite edges of said extension, means for attachment of a wire to said 30 extension, a jaw having pivots extending from opposite sides into openings in the posts rising from the supporting jaw, said pivoted jaw having a strut rest with an opening therein, a strut having pivots located in openings in the posts on said extension and its opposite end located within the opening in said strut rest, and a spring mounted on said strut. 35
5. A terminal for electrical devices, said terminal comprising two jaws pivotally connected, a strut pivotally mounted upon one of said jaws and in engagement with the other jaw, and a spring mounted upon said strut and exerting a force to close the free 40 ends of the jaws together. 45
6. A terminal for electrical devices, said terminal comprising two jaws pivotally connected, a strut pivotally mounted upon one of said jaws, a rest comprising an overturned end from the other jaw, and a spring 50 located on said strut and thrusting against said rest to force the free ends of said jaws toward each other. 55
7. A terminal for electrical devices, said terminal comprising two jaws pivotally connected, each of said jaws having spring resisting members projecting laterally from the jaws, and a spring disposed longitudinally of the jaws and exerting a thrust longitudinally of the jaws and against said 60 members to normally force the free ends of said jaws toward each other. 60

ANDREW C. SAXE.
